UNDERGARMENT

Mathias Imershein, New York, N. Y., assignor to Grace-form-Camlin Corset Co., Inc., New York, N. Y., a corporation of New York

Application May 1, 1952, Serial No. 285,397

5 Claims. (Cl. 2-36)

This invention relates to woman's undergarments; and, more particularly, to that class of such undergarments which includes girdles and corsets.

The general object is to provide a novel undergarment of this class, said undergarment being specially suited for the comfortable confinement of bulges of the wearer's flesh in the regions of the diaphragm, abdomen, buttocks, and thighs.

A particular object of the invention is to provide a novel girdle having front and rear portions each comprising right and left panels extending from the waist line to the lower edge of the girdle, said panels having pronounced horizontal stretchability, and being separated by a central inelastic panel, said last named panel being composite and including two series of parallel bands, the series crossing each other diagonally. In connection with the present object the girdle is provided with inelastic side panels, also extending from the waist line of the girdle to the lower edge thereof, one of said side panels connecting the right elastic panels of the front and rear portions and the other side panel connecting the left elastic panels of these portions. The principal purpose of this construction is to provide inelastic panels for covering those portions of the wearer's torso which are naturally less reinforced by bone and muscle and are consequently more apt to bulge. As will be seen, the inelastic central panel of the front portion of the girdle, being specially reinforced by the crossed series of parallel bands, and preferably shaped generally to conform to the softer portions of the front of the wearer's body, provides a means for flattening the diaphragm and the abdomen. The inelastic central panel of the rear portion of the girdle, also being specially reinforced by another crossed series of parallel bands, and also preferably shaped to conform to the softer portions of the rear of the wearer's body, provides equally efficient means for flattening bulges of the small of the back and of the buttocks. The inelastic side panels adequately confine the bulges of the outsides of the thighs; and the interspersed elastic panels, having pronounced horizontal stretchability, and overlying firmer portions of the wearer's body, permit of comfortable mobility while maintaining the inelastic panels in taut condition.

A further object of the invention is to provide a girdle, or like undergarment, having the features described above, and being sleeve-shaped to conform to the wearer's trunk from the waist down, with means for opening and closing the sleeve at one side thereof between the waist line and a point therebelow, for facilitating donning and removal of the garment.

Another object is to provide a girdle, or like undergarment, as described above, having substantially vertical bones or other suitable reinforcing members applied to the front and rear portions and the side panels, and extending downwardly from the waist line, to prevent the garment from rolling from the waist.

A particular feature of the invention is the provision of shaped inelastic panels in the center of the front and rear portions of the garment. The provision of inelastic central panels at the front and rear of garments of this type, these being joined by elastic panels having pronounced horizontal stretchability, is shown in applicant's United States Patent Re. 21,595; but the inelastic panels are arranged merely to cover the front and rear portions of the wearer's body broadly, and the outlines of these panels are not shaped to conform to

2

the outlines of those softer portions of the wearer's body sought to be flattened. Also, in the structure shown in the patent referred to, no inelastic side panels are provided, and, accordingly, the bulges at the outsides of the thighs of the wearer can be confined only by elastic material. It has been found that the introduction of inelastic side panels produces a more satisfactory and more attractive garment.

In the present invention the front central inelastic panel is of considerable width at that part corresponding to the normal region of greatest natural bulge of the abdomen and where the maximum flattening effect is desirable; and, downwardly from such part, the panel narrows to a point at the lower edge of the garment. The rear central inelastic panel is of greatest width at that part corresponding to the normal region of greatest natural bulge of the buttocks. The crossed series of parallel bands with which these two panels are reinforced have the effect of evenly distributing the compression desired at the body portions mentioned above; and the girdle, when worn, produces a very graceful appearance of the lower portion of the wearer's trunk, yet does not impair mobility or discomfort her.

These and other objects and features of the invention will be more fully understood from the following description and from the drawing, in which one form of the invention is shown.

In the drawing:

Fig. 1 is a front view, partly broken away, of a girdle constructed in accordance with the present invention.

Fig. 2 is a rear view of the girdle.

The girdle is a sleeve, designed to conform to the lower portion of the trunk of the wearer and adapted to be partly opened and closed at one side. The sleeve comprises, as will be seen, a series of alternating elastic and inelastic panels, all extending from the waist line of the garment to the lower edge thereof.

The front portion 1 of the girdle, seen in Fig. 1, comprises a central composite inelastic panel 2, the outline of which approximates the outline of the softer regions of the front of the wearer's body, i. e., the diaphragm and the abdomen. It will be noted that the widest part of the panel, at 3, corresponds to the normal region of greatest natural bulge of the abdomen. Downwardly from this part the panel tapers toward the lower edge of the garment. Panel 2 is a laminated structure. Its front and rear plies 4 and 5 may be of net, lace, or other fabric. Between these two plies is a third ply 6, preferably of marquisette. Extending from side to side of the panel, except at the narrowed part near the lower portion of the garment, and secured to the ply 6 are two diagonally crossed series of parallel bands 7 of fabric having a considerable tensile strength. In fact the resistance of the panel to horizontal stretch may derive almost wholly from the bands 7, and the plies 4 and 5, which cover the network of bands, and ply 6, may be of relatively flimsy material, as suggested. Applied to the rear of the panel, on either side of its center line, and extending downwardly from the waist line of the garment, are two narrow vertical pockets 8, each adapted to carry a reinforcing bone 8a to prevent the girdle from rolling at the waist in the front.

Secured to the sides of panel 2 are elastic panels 9 and 10, each having pronounced horizontal stretchability. Panels 9 and 10 are otherwise hand to each other, but otherwise alike. The horizontal stretchability of panels 9 and 10 is modified in certain areas by parallel lines 11 and 12 of zigzag or other suitable stitching, as clearly shown in Fig. 1, such lines being disposed as guys to tighten panel 2 in the greatest degree at that part corresponding to the region of maximum natural protrusion of the abdomen.

The rear portion 13 of the girdle, seen in Fig. 2, comprises a central composite panel 14, the outline of which approximates the outline of the softer regions of the back of the wearer's body, i. e., particularly the lobes of the buttocks. Accordingly, the widest part 15 of the panel 14 is near the lower edge thereof. Like panel 2, panel 14 is a laminated structure. Its outer and inner plies 16 and 17 may be of net, lace, or other fabric. Extending from side to side of panel 14, except at the upper-

most part thereof, are another pair of diagonally crossed series of parallel bands 18 of fabric similar to that series of bands 6 at the front of the garment. The crossed series of bands 18 are secured to the inner ply 17 of panel 13 similarly as the crossed series of bands 7 are secured to the middle ply 6 of panel 2 at the front of the garment. As in the case of panel 2, the resistance of panel 14 to horizontal stretch may derive almost wholly from its network of bands, and the covering plies 16 and 17 may be of flimsy material. Applied to the inner surface of panel 14, on either side thereof, and extending downwardly from the waist line of the girdle, are two narrow and substantially vertical pockets, not shown, each adapted to carry a reinforcing bone 19, to prevent the garment from rolling at the waist in the back. 15

Secured to the sides of panel 14 are elastic panels 20 and 21, each having pronounced horizontal stretchability. Panels 20 and 21 are other hand to each other, but otherwise alike.

Panel 14 is cut away at the waist line to provide a Y in which a triangular panel 22 of elastic fabric is inserted, the fabric having pronounced horizontal stretchability. Panel 22 is provided for the purpose of rendering the girdle elastic at the small of the wearer's back. 25

The front and rear portions of the girdle are connected together by side panels 23 and 24. These panels are of suitable inelastic fabric, and may be provided with boning or

Panel 10 of the front portion, while permanently secured by suitable stitching to side panel 23 at the lower portion of the girdle, is releasably secured to the side panel 30 at the upper portion of the garment by means of a zipper 25 whereby the sleeve may be opened for donning and removal.

Usual garters 26 are provided. It will be understood from the foregoing that both the front and rear net work of bands are sandwiched between front and rear net work of bands are sandwiched between plies of material, and that neither network may come in direct contact with the body of the wearer, and so cause discomfort. As each network of bands is secured to a ply of fabric, the compression effect of the network is thereby evenly distributed over the related parts or parts of the body. Further, with the networks of bands covered and partly obscured by lace or other suitable material, the networks of bands are not visible when the garment is worn with a sheer outer garment; and no impression of said networks is transferred to said outer garment. 45

I claim:

1. A girdle comprising, inelastic front, rear, and side panels, and elastic panels interposed between said front and side panels and said rear and side panels, all said panels extending from the top to the bottom edge of said girdle, said front panel being centrally located in the front of said girdle and said rear panel being centrally located in the back of said girdle, said front and rear panels being laminated structures having an inner and an outer web with a network of diagonally crossed series of parallel bands of pliant fabric between said webs, said bands extending from side to side of said last named panels. 55

2. A girdle comprising, inelastic front, rear, and side

panels, and elastic panels interposed between said front and side panels and said rear and side panels, all said panels extending from the top to the bottom edge of said girdle, said front panel being centrally located in the front of said girdle, and being a laminated structure having an inner and an outer web with a network of diagonally crossed series of parallel bands of pliant fabric between said webs, said bands extending from side to side of said last named panel.

3. A girdle comprising, inelastic front, rear, and side panels, and elastic panels interposed between said front and side panels, and said rear and side panels, all said panels extending from the top to the bottom edge of said girdle, said rear panel being centrally located in the back of said girdle, and being a laminated structure having an inner and an outer web with a network of diagonally crossed series of parallel bands of pliant fabric between said webs, said bands extending from side to side of said last named panel.

4. A girdle comprising, alternately, four elastic panels having pronounced horizontal stretchability and four inelastic panels, all said panels extending from the top to the bottom edge of said girdle, with one of said inelastic panels being centrally located in the front of said girdle, another of said inelastic panels being centrally located in the back of said girdle, and the other two inelastic panels being respectively located at the sides of said girdle, the front and back inelastic panels being laminated structures having an inner and an outer web with a network of diagonally crossed series of parallel bands between said webs, said bands extending from side to side of said front and back inelastic panels.

5. The girdle of claim 4 wherein said front inelastic panel is shaped to accord approximately with the more protuberant portions of the diaphragm and abdomen to the wearer, and said back inelastic panel is shaped to accord approximately with the more protuberant portions of the buttocks of the wearer, and wherein the elastic panels to the right and to the left of said front inelastic panels are provided with rows of reinforcing stitching radiating outwardly with respect to the center of said front inelastic panel for pronouncedly tightening that portion of said front inelastic panel adapted to overlie the central portion of the abdomen.
